United States Patent Office

Des. 208,530
Patented Sept. 12, 1967

208,530

SPONGE MOP

Hyman Hoffman, Los Angeles County, Calif.
(14333 Addison St., Sherman Oaks, Calif. 91403)

Filed Jan. 23, 1967, Ser. No. 5,516

Term of patent 14 years

(Cl. D9—2)

The broken line showing of a mop handle in FIGURE 1 is for illustrative purposes only.

I claim:

The ornamental design for a sponge mop, substantially as shown and described.
